J. D. COOPER,
RAILWAY SWITCH,
APPLICATION FILED DEC. 3, 1919.

Patented July 18, 1922.

2 SHEETS—SHEET 2.

UNITED STATES PATENT OFFICE.

JAMES D. COOPER, OF TORONTO, ONTARIO, CANADA.

RAILWAY SWITCH.

1,422,836.

Specification of Letters Patent.

Patented July 18, 1922.

Application filed December 3, 1919. Serial No. 342,164.

To all whom it may concern:

Be it known that I, JAMES DIXON COOPER, a subject of the King of Great Britain, and resident of the city of Toronto, county of 5 York, Province of Ontario, in the Dominion of Canada, have invented certain new and useful Improvements in Railway Switches, described in the following specification and illustrated in the accompanying drawings, 10 that form part of the same.

The principal object of this invention is to eliminate the difficulties and dangers in operating railway switches, and to devise a simple and effective switch operating mechanism which may be controlled from a moving vehicle.

A still further object is to devise a mechanism which will not be liable to get out of order and is of extremely simple construction.

The principal feature of the invention consists in the novel construction and arrangement of parts, whereby the switch is operated in advance of the moving vehicle by 25 a longitudinally movable member which is operated by means of a member extending from the vehicle.

In the drawings, Figure 1 is a plan view of the switch operating apparatus of the 30 type particularly adaptable for a street railway service.

Figure 2 is a longitudinal mid-sectional view through the device shown in Figure 1, showing diagrammatically the means carried by the vehicle for actuating the switch operating mechanism.

Figure 3 is a cross sectional view through the line *a—a* of Figure 2.

Figure 4 is a horizontal sectional view 40 through the portion of the device directly co-operating with the member carried by the vehicle, showing the reciprocating member in the forward locked position.

Figure 5 is a vertical sectional view 45 through the line *b—b* of Figure 1.

Figure 6 is an enlarged longitudinal sectional view of the switch operating member taken on the line *c—c* of Figure 1.

Figure 7 is a diagrammatic plan view 50 showing a modified form of the invention.

Figure 8 is an enlarged longitudinal sectional view of the member operated by contact with the engaging member from the vehicle.

55 The difficulties of operation of switches in

railway service and the dangers incident thereto are very well known and this invention contemplates a mechanism which will enable the driver of the vehicle to operate the switch in advance of the vehicle by mechanical means which will be positive in its operation.

The form of the invention illustrated in Figures 1 to 6 is particularly adaptable for street railway service, though it may be applied to other types of railways.

In the type shown a recess 1 is arranged between the rails 2 at a point where the rails diverge. The switch point 3 is of the free street railway type resting in a socket 4 in the rail structure.

The point 3 is provided with a pin 5 which projects downwardly therefrom through a slot in the base of the socket.

A guide member 6 formed with down turned side flanges 7 extends between the rails 2 and in this guide is slidably supported a bar 8, said bar having a slot 9 therethrough to receive the pin 5 of the switch point 3. The inner end of the bar 80 is formed with a slot 10 in which is slidably arranged a cross head 11 carrying on its lower side a roller 12.

Each side of the cross head is arranged a coil compression spring 13 supported by the 85 guide rods 14.

A flanged guide 15 is arranged centrally of the recess 1 having a centrally grooved depression 16 and on top of this flanged guide is arranged a switch operating member 17 which is formed with longitudinally flanged ribs 18 engaging the side flanges of the guide member 15 in sliding contact.

The member 17 is of an elongated oval shape having raised side flanges 19 and a raised central portion 20 which forms a pair of longitudinal channels 21 and 22 which join together at the ends of the central portion.

Secured to the side walls of the central portion 20 are spring members 23 and 24 which form continuations of the guide ways and are adapted to spring in one direction to allow the roller 12 to pass from one channel to another at opposite ends.

In Figure 1 the member 17 is shown with the switch operating roller 12 in the extreme end of the channel 21. Upon the longitudinal movement of the member 17 the roller will follow the channel 21, consequently 110

- drawing the bar 8 across the rails to bring the end of the slot 9 into engagement with the pin 5 and to thus swing the switch point. As the member 17 moves onward the roller 5 follows the elongated oval shape of the channel 21 and pressing aside the spring 23 the roller enters the channel 22. Upon the return movement of the member 17 the roller follows the channel 22, consequently the bar 8 is moved in the opposite direction until the other end of the slot engages the pin 5 of the switch point and swings the point back to its original position and as the member 17 continues its 15 movement, the roller is brought back to its central position and the opposite end pressing aside the spring switch 24 and again entering the channel 21 ready for the next operation.
- 20 A bar 25 is rigidly secured to the end of the member 17 on the side of approach to the switch. A coil spring 26 is arranged in the groove of the guide 15, one end being connected to 25 the member 17 and the other end being rigidly secured and said spring is adapted to operate the member 17 in the reverse direction following the movement toward the switches by the mechanism hereinafter described.
- 25 A bar 27 is pivotally connected to the bar 25 and extends into a casing 28 arranged in the road bed. Within the casing 28 is arranged a pair of vertical walls 29 each side 30 of the longitudinal centre and between which the bar 27 operates. Secured to the inner side of each of the walls 29, at the top, are the guide members 30 which are provided with downwardly extending ends 31 at the ends adjacent to the switch.
- 35 The free ends of the bar 27 is provided with rollers 32 which are adapted to engage the projections 31 of the top guides 30 and upon engagement the bar 27 is moved downwardly into contact with the lower guides 33. Arranged between the upper and lower guides is a metal strip 34 upon which the rollers 32 run in the forward movement of 50 the bar and said rollers when operating on the lower guides move beneath said strips. The end of the lower guide farthest from the switch is curved upwardly and the metal strip 34 is formed with a spring end meeting the upward curve of the lower guide, said spring end being adapted to lift upwardly to allow the rollers to travel up the incline of said guides to return the rollers to the upper guide and immediately the rollers 55 pass beyond the end of the metal strip into the upper guide the spring end returns to its normal position forming the bottom of the upper guide.
- 60 The bar 27 is provided with an upwardly projecting member 35 formed in a pocket

shape open at one end which is adapted to form a contacting member to effect the operation of the mechanism.

The vehicle is provided with a shoe 36 here shown supported upon pivotal links 70 and arranged to be raised or lowered. This shoe when in its lowered position enters between the upper guides in the casing 28 and engages the projecting member 35 on the bar 27, consequently the bar is moved 75 longitudinally, the rollers moving in the upper guides and upon coming in contact with the down turned portion of the upper guides, the bar is drawn downwardly clear of the shoe.

80 The forward movement operates the switch operating member 17 to move the switch and as the bar 27 is dropped downwardly and clears the shoe, the car proceeds upon its way around the switch. The coil spring 85 26 is then drawn out and placed under tension and it is locked in this position by a downwardly projecting stop 38 on the bar 27.

85 A cross bar 39 is slidably arranged in the 90 slots 40 in the vertical walls 29 of the casing 28 and engages the stop lug 38 when the bar 27 drops to the lower position. One end of the cross bar 39 carries a roller 41 which roller engages a longitudinally slid- 95 able plate 42 having a notch 43 in which the roller normally rests.

95 A spring 44 extends through a slot in the opposite end of the cross bar and holds the roller in contact with the notched plate. 100

The plate 42 is operated by means of a rocker arm 45, the spindle of which extends upwardly having a horizontally turned end 46 extending across the slot 47 between the guard plates 48. The switch remains turned 105 as previously indicated while the switch operating member is locked in the forward position and upon the approach of the vehicle if it is desired that the switch be moved, the shoe is lowered and engaging the member 46 swings the rocker arm 45 to operate the plate 42 and the longitudinal movement of the plate pulls the cross bar 39 against the pressure of the spring 44 to bring a notch 49 in the said cross bar into alignment with the stop 38. The bar 27 is thus released and the coil spring 26 moves the switch operating member 17 to return the switch to its normal position and the bar 27 moves inwardly and rises to the upper 115 guide way so that when the next vehicle approaches the shoe may be brought into direct contact with the bar 27 to again operate the switch as desired.

120 The mechanism is extremely simple and very positive. There is nothing of a delicate nature to get out of order and it is equally applicable to street railway service and to steam or electric high speed railways.

125 In Figures 1 and 3 a semaphore is shown 130

connected with the switch operating bar 8 which will indicate the position of the switch. It will of course be understood that the connections between the member 17 and

5 the mechanism contained in the casing 28 may be any desirable length.

In operating on steam roads it is desirable that the distance of operation be extended and it is also desirable that the switch 10 be locked. The member 17 is therefore dispensed with and the other mechanism may be modified as shown in Figures 7 and 8.

In this construction the casing 50 is set some distance from the switch and in the 15 side walls of this casing are formed the upper and lower guide-ways 50' and 51 separated by the spring plate 52 and a guide 53 forms a continuation of the lower guide-way.

20 A bar 54 is provided intermediate of its length with a member 55 having rollers extending laterally into the guide-way 53. At the forward end of this bar is secured a head 56 having rollers 57 operating in the guide-ways 50' and 51, said head having an upward projecting portion 58 adapted to be engaged by the shoe on the vehicle.

A lug 59 is formed upon the head 56 and to this lug is secured a cable 60 connected 30 with a piston 61 arranged in a dash pot cylinder 62 which is of corresponding length to the length of travel of the head 56, said cylinder having small openings 63 at the top to allow of the escape of air in restricted 35 quantities.

To the opposite end of the bar is secured a link 64 which connects with a slidable member 65 operating in a guide 66, which member is provided with a longitudinal slot 40 67 having an offset end 68.

The switch operating bar 69 is provided with a pin 70 extending into the slot 67.

When the head 56 is in the upper guide-way the offset portion 68 of the slot 67 engages the pin and if an approaching train desires to change the switch the shoe is lowered to engage the head pushing it until it is forced downwardly into the lower guide. This moves the sliding member 66 50 and the slot operates the switch.

A spring lock member 71 is arranged in the bottom of the casing 50 and engages the head and holds it from returning along the lower guide-way.

55 Cables 72 and 73 are secured to this spring lock and extend downwardly over a pulley 74, one of said cables extending in each direction from the switch and each being connected to a suitable lever 75 arranged 60 in the trackway so that the operator may by dropping the shoe pull upon the cable and release the lock to allow the switch to be returned by the action of the weight in the dash pot.

65 An extension cable 76 may be arranged

around the switch curves so that after a train has passed on to a siding it may return the switch to normal for a through train.

Many of the details of the structure herein shown and described may be altered without departing from the spirit of the invention.

What I claim as my invention is:—

1. In a railway switch mechanism, the 75 combination with the switch and a vehicle, of a transversely slidable member operatively connected with the switch and having a downwardly projecting pin, a longitudinally slidable member having a pair of interconnected 80 guide-ways engaging the pin of said switch operating member and adapted to move said switch operating member in the reverse direction according to its direction of movement, a bar pivotally connected to 85 said longitudinally movable member, a casing having vertical side walls formed with guide-ways therein, said guide-ways being separated by a plate member having one end closing the lower guide-way and adapted to 90 spring upwardly, laterally projecting pins on said bar operating said guide-ways, a shoe carried by the vehicle adapted to be lowered into contact with said bar, means for locking the bar in the forward position, means 95 for returning the bar, and means actuated by the shoe for releasing said locking means.

2. In a railway switch mechanism, the 100 combination with the switch and a vehicle, said switch having a downwardly extending pin, a bar arranged transversely of the switch having a slot to receive said pin, a guide-way supporting said bar, a pin resiliently connected with the bar, a longitudinally 105 movable member operating transversely of said bar and having an elongated oval shaped member formed with a pair of guide-ways interconnected at the ends, spring plates crossing the ends of the guide-ways adapted to direct the pin of the cross member alternately from one guide-way into the other on the reciprocation of said member, and means for reciprocating said guide member operable from the vehicle. 110

3. In a railway switch mechanism, the combination with the switch and vehicle, of a transversely slidable member connected with said switch, a longitudinally operable member adapted to operate said transverse member, a bar pivotally connected to said longitudinally movable member and having laterally extending members, a pair of horizontal guide-ways arranged one above the other engaging the lateral extensions from 120 said bar, means for directing said extensions into the lower guide from the upper and to the upper from the lower, a locking member extending transversely of said lower guide-way adapted to engage said bar, a shoe car- 125 130

- ried on a vehicle adapted to engage said bar, means operable by the shoe for withdrawing said locking bar from engagement with said operating bar, and means for returning the bar and switch operating mechanism to their normal positions.
4. In a railway switch mechanism, the combination with the switch and a vehicle, of a laterally movable member operating said switch, a longitudinally movable member having a grooved offset to effect the lateral movement of said switch member, a member connected with said longitudinally movable member and adapted to be operated from the vehicle, a shoe carried on the vehicle adapted to engage and operate said member, means for automatically effecting the disengaging of said member from said shoe, means for automatically returning said member to its normal position, means for locking said member from returning to its normal position, and means adapted to be operated by the shoe for unlocking said locking means.

5. In a railway switch mechanism, the combination with the switch and a vehicle, of a laterally movable member operating said switch, a longitudinally movable member having a grooved offset to effect the lateral movement of said switch member, a member connected with said longitudinally movable member and adapted to be operated from the vehicle, a shoe carried on the vehicle adapted to engage and operate said member, means for automatically effecting the disengaging of said member from said shoe, means for automatically returning said member to its normal position, a notched bar extending across the path of movement of said operating bar and spring held to engage and lock said bar, a cam member operatively connected with said bar and adapted to move it to a releasing position, and an arm connected with said cam member extending across the path of travel of the vehicle shoe.

J. D. COOPER.
